DESIGN FOR A COMBINATION WATER BOTTLE AND ICE BAG OR SIMILAR ARTICLE

Richard C. Jones, Stow, Ohio, assignor to American Anode Inc., Akron, Ohio, a corporation of Delaware

Application July 25, 1941, Serial No. 102,477

Term of patent 14 years

To all whom it may concern:

Be it known that I, Richard C. Jones, a citizen of the United States, residing at Stow, in the county of Summit and State of Ohio, have invented a new, original, and ornamental Design for a Combination Water Bottle and Ice Bag or Similar Article, of which the following is a specification, reference being had to the accompanying drawing, forming a part thereof.

In the drawing, Fig. 1 is a side elevational view of a combination water bottle and ice bag or similar article embodying my new design, the article illustrated being intended for use in applying hot or cold treatments to a human foot;

Fig. 2 is a plan view of the article of Fig. 1.

The bottom of the article is substantially plain. I claim:

The ornamental design for a combination water bottle and ice bag or similar article, as shown and described.

RICHARD C. JONES.
